UNITED STATES PATENT OFFICE.

WILLIAM R. BROSS, OF BABYLON, NEW YORK.

JACK FOR AUTOMOBILES.

1,130,472.

Specification of Letters Patent.

Patented Mar. 2, 1915.

Application filed May 14, 1914. Serial No. 838,416.

To all whom it may concern:

Be it known that I, WILLIAM R. BROSS, a citizen of the United States of America, and a resident of the town of Babylon, county 5 of Suffolk, State of New York, have invented a new and useful Improvement in Jacks for Automobiles, of which the following is a specification.

This invention relates to lifting jacks for 10 automobiles, and particularly designed for use in lifting or raising a portion of the car and provided with an adjustable means for maintaining an element or part of the car in a desired position while the jack is in 15 raised position.

More specifically, my invention comprises a lifting jack to a fixed portion of which is secured a standard provided with a holding element. Such arrangement is useful, particularly 20 when used in connection with automobiles, in which case the holding element serves to maintain a raised wheel in a desired position when the car has been "jacked" up, or similarly hold in position any other 25 part of the car which is otherwise given freedom of motion when the car has been raised, and thereby avoid possible damage or derangement of the parts.

Preferably the holding element is made 30 adjustable to accommodate different sizes of articles to be held thereby, as different sizes of wheel spokes, or the like. Furthermore, the holding element and its mounting on the jack is preferably constructed to be 35 capable of being pushed or collapsed into reduced dimensions to facilitate storage in the automobile.

Further features of my invention will be more fully understood from the following 40 description and the accompanying drawings, in which—

Figure 1 is an end elevation of a jack constructed in accordance with my invention; Fig. 2 is a top plan view of same; 45 Fig. 3 is a detail sectional elevation of self-holding coupling of the arm carrying the holding member with the body of the jack; and Figs. 4 and 5 are detail views of parts of the self-holding coupling.

50 Referring to the drawings, the jack 1 is of the ordinary single or double stroke type operable by vertical movement of the handle 2. The casing 3 of the jack is shown provided with the lug 4 from which projects 55 the stud 5. The lateral face 6 of lug 4 is provided with four spaced cams 7. The

stud 5 passes through an opening in the block 8, and the face of the block 8 opposite the face 6 of lug 4 is provided with four spaced cams 9 cooperating with the spaced 60 cams 7. Threaded on the end of stud 5 is the nut 10 and between the nut 10 and block 8 is positioned the spring 11. By such construction, upon proper tightening of nut 10, the block 8 will be automatically held in 65 any one of the four positions determined by the four sets of cam surfaces 7, 9.

The arm or rod 12 passes through a recess 13 in block 8, and positioned therein by means of a winged nut or set screw 14. At 70 one end of the rod 12 is provided the holding member comprising the fingers 15, 15, pivoted at 16 and tensioned by the distending spring 17. By forcing the manipulating ends 18, 18, together, the forward 75 ends of fingers 15, 15, will be moved apart. Thus, in the use of my invention, particularly for "jacking" up a front axle 19 of an automobile, the handle 2 of the jack will be operated as usual, during which operation the arm or rod 12 may be in the vertical position. After the axle has been raised the desired amount, the arm 12 will be moved to horizontal position and the fingers 15, 15 opened sufficiently by pressing 80 together the ends 18, 18 to pass around a spoke 20, whereupon releasing the ends 18, 18 the spring 17 will force the fingers 15, 15 into engagement with the spoke 20. If necessary, to effect the desired adjustment, 85 the set screw or winged nut 14 will be loosened to allow the arm or rod 12 to be moved to the proper length. In such position of the apparatus, the wheel will be held rigid by the fingers 15, 15, grasping the 90 spoke 20, thereby facilitating the operation of pumping air into the tires, or of removing or putting on a tire, etc. It will be noted that in the operative position of the apparatus the rod or arm 12 is rigidly held 100 against forces in the horizontal plane and perpendicular to the rod or arm 12, notwithstanding the adjustable coupling.

Upon releasing the fingers 15, 15, from the spoke of the wheel, the arm 12 may be 105 pushed away from the wheel and then swung into its vertical position, in which position my combined jack and holding device occupies practically the same space for storage as an ordinary jack.

The cam or rod 12 may also be provided at its other end with another form of hold-

ing member comprising the pointed lug 21 adapted to be inserted between the leaves of a spring, such as a body spring of the automobile. Thus, to spread the leaves of a spring, the jack is applied to the adjacent axle or to the bottom of the spring and operated to raise the same; the arm 12 is then moved to vertical position and the lug 21 inserted between the leaves of the spring desired to be spread apart, after which the set-screw 14 is tightened to hold the arm 12 in position. By allowing the movable or rack element of the jack to drop, the lug 21 will retain in raised position the spring leaf under which it is inserted; and the lower leaf will drop owing to the removal of the lifting force previously exerted by the movable or rack element of the jack, in which position the face of the leaf of the spring may be readily inspected, cleaned, oiled, or otherwise treated. After such treatment, the rack or movable element of the jack is again raised sufficiently and the arm 12 turned to pull out the lug 21, and thus readily effect the desired results without subjecting any part of the automobile to extreme strain. Similarly other forms of holding members may be employed in combination with the jack to secure other results as may be desired.

Whereas I have described my invention by reference to specific embodiments thereof, it will be understood that many changes and modifications may be made without departing from the invention.

What I claim and desire to secure by Letters Patent is:—

1. The combination with a lifting jack,

Copies of this patent may be obtained for five cents each, by addressing the "Commissioner of Patents, Washington, D. C."

of an arm, means for rotatably mounting said arm on said jack, said means comprising a stud carried by said jack and a member pivoted to said stud, said member having a recess receiving said arm and a set screw for positioning said arm on said member at any desired point longitudinally of said arm.

2. The combination with a lifting jack, of an arm, a tool element carried at one end of said arm, means for rotatably mounting said arm on said jack, said means comprising a stud fixed to a stationary portion of said jack and a member pivoted to said stud, said member having a recess receiving said arm and a set screw for positioning said arm on said member at any desired point longitudinally of said arm.

3. The combination with a lifting jack, of an arm, a stud carried by the stationary element of the jack, a block rotatably mounted on said stud, cam elements, a spring coöperating with said cam elements and said block to hold said block at certain predetermined positions relatively to the stationary element of the jack, said block being provided with a recess receiving said arm, and fastening means for positioning said arm at any desired point longitudinally of said arm.

In testimony whereof I have signed this specification in the presence of two subscribing witnesses.

WILLIAM R. BROSS.
